ELECTRON GUN

James W. Schwartz, Princeton, N.J., assignor to Radio Corporation of America, a corporation of Delaware

Application July 22, 1957, Serial No. 673,234

7 Claims. (Cl. 315—15)

This invention is directed to an electron gun structure for use in a cathode ray tube.

A cathode ray tube utilizes an electron gun for providing a narrow beam of electrons which is scanned over a fluorescent screen within the tube. The electrons of the beam are derived from a heated, thermionic cathode electrode and are urged through an apertured control grid electrode by appropriate accelerating fields. The control grid electrode may be a conducting plate structure having a single aperture or a plurality of apertures positioned close together and overlying a portion of the emitting surface of the cathode. There is a range of operating voltages applied to the control grid electrode, the lowest voltage of which prevents electrons from passing through the control grid aperture. This potential is known as the cut-off potential of the tube and is usually a potential negative to that of the cathode electrode. The other potentials at which the control grid is operated are more positive than the cut-off potential and are applied to the control grid to vary the electron flow through the control grid aperture.

In normal tube operation, incoming signal pulses are applied between the cathode electrode and the control grid to supply a varying potential difference between these two electrodes to form a corresponding variation in the electron flow through the control grid aperture. This produces a modulated electron beam, which by appropriate electrode structure is focused on the fluorescent screen of the tube. As the beam is deflected across the surface of the fluorescent screen, its modulation produces a variable light pattern, which is an optical reproduction of the incoming signals applied to the tube.

Cathode ray tubes of the type described, which are used for television viewing purposes and utilizing a cathode-control grid arrangement, may require an operative potential range of control grid voltages of up to 100 volts from cut-off potential. A normal control voltage range, however, is in the order of 50 to 70 volts from cut-off to maximum beam current. These voltage ranges are excessive and require considerable amplification of the incoming video signal to operate the tube effectively.

As the control grid is operated within its operative range from cut-off, the focus of the electron beam at the fluorescent screen varies with change in potential of the control grid. This is an undesired effect since loss of beam focus at the fluorescent screen reduces the resolution of the picture. Another disadvantage of conventional cathode ray tubes is that the cathode emitting surface is aligned with the pre-deflection beam path. Since the high energy electron beam will tend to ionize residual gas molecules within the tube, positive gas ions are formed and are directed back along the beam path and bombard the exposed cathode emitting surface. This tends to destroy the effectiveness of the cathode and thus shortens the life of the tube.

It is thus an object of this invention to provide an electron gun for a cathode ray tube which has low voltage requirements for control grid operation.

2

It is another object of the invention to provide a novel electron gun for a cathode ray tube requiring a small change in control voltage from cut-off to full beam current.

- 5 It is a further object of the invention to provide a novel electron gun for a cathode ray tube having low voltage requirements for the control grid electrode and in which the beam focus at the fluorescent screen is independent of the beam current.
- 10 The invention is in a novel gun structure utilizing an annular cathode electrode having an emitting area on the inner surface of the annulus. A control grid electrode and an accelerating electrode are formed as coaxial rings disposed within the annular cathode surface. A probe electrode directs electrons emitted by the cathode surface along the axis of the annular cathode through a small object aperture in a beam masking electrode. Electrons passing through the object aperture are focused on the fluorescent screen.
- 15 Figure 1 is a schematic showing of a cathode ray tube utilizing a novel gun structure in accordance with the invention.
- 20 Figure 2 is an enlarged sectional view of the electron gun structure in accordance with the invention.
- 25 Figure 3 is a sectional view of the structure of Figure 2 in the plane of section line 3—3.
- 30 Figure 4 is a graphical showing of the operating characteristics of the novel gun structure shown in Figure 2 under certain specific conditions of operation.
- 35 Figures 5 and 6 are partial sectional views showing modifications of the gun structure of Figure 2.
- 40 Figure 1 shows a cathode ray tube utilized for television purposes, which consists of an evacuated envelope having a bulb portion 10 and a tubular neck portion 12 extending from the smaller end of the bulb 10. Within the envelope neck portion 12 there is mounted an electron gun structure 14 consisting of a plurality of electrodes aligned along the axis of the neck portion. The gun structure forms an electron beam from electrons emitted by a thermionic cathode electrode and directs the beam onto a fluorescent screen within the tube. The fluorescent screen consists of a thin layer 16 of phosphor material coated on the inner surface of a transparent face plate 18 closing the large end of the tapered bulb 10. The electron beam is scanned over the surface of phosphor screen 16 by magnetic fields formed from appropriately designed coils mounted within a neck yoke structure 20.
- 45 The electron gun 14 is shown in detail in the enlarged sectional view of Figure 2. A cathode electrode 22 is formed as an annular ring structure having a U-shaped cross-section, as shown. The cathode ring 22 is fixed to a mounting ring 24 positioned concentrically with the cathode ring 22. Between the two rings 22 and 24, and as shown in more detail in Figure 3, are a plurality of metal straps 26 each having one end fixed to the cathode ring 22 across its U-shaped channel portion and the other end fixed to the inner surface of the support ring 24. This supporting structure permits the cathode ring 22 to retain its axial position within the gun structure, when the cathode ring 22 becomes heated to a high temperature during tube operation. Any expansion of the cathode ring 22 will cause the ring to rotate about its axis slightly and maintain its axial position relative to the other gun electrodes constant. Cathode mounting ring 24 is in turn supported by two metal studs 28 each welded at one end to the ring 24 and having the other end fixed within glass support rods 30.
- 50 The inner surface of the cathode ring 22 is coated with a thermionic emitting material to provide a source of electrons. Closely spaced from this coated surface is a control grid structure consisting of a pair of centrally apertured circular control grid plates 32 and 34 whose
- 55
- 60
- 65
- 70

peripheries are fixed into the glass support rods 30. Plate 32 has a short cylindrical extension or tubular member 36 projecting over the coated surface of cathode 22. In a similar manner, plate 34 has a short cylindrical projection or tubular member 38 extending axially toward the tubular member 36. The two plates 32 and 34 are in this example identical in all dimensions and are rigidly fixed to the glass rods so that they are coaxial with the annular cathode 22. The spacing between the first pair of tubular members 36 and 38 of the control grid plates forms an annular open space overlying the cathode surface and is utilized to control the electron emission from the adjacent surface of the cathode ring 22.

A second pair of circular plates 37 and 39 of identical size and shape, are supported by the glass rods 30. Plate 37 has a central aperture with a short cylindrical wall portion or tubular member 40 extending from the periphery of the aperture and overlying the tubular member 36 of ring 32. Plate 39 in a similar manner, has a cylindrical wall extension or tubular member 42 extending from the periphery of its central aperture toward the oppositely extending tubular member 40 of ring 37. The second pair of tubular members 40 and 42 are spaced apart to form an annular opening between them which is aligned with the annular opening between tubular members 36 and 38.

An electrode plate structure 44 is fixed to the glass rods 30 in a plane parallel to the plane of the circular plate 37 and closely spaced therefrom. At the center of plate 44, and symmetrically formed relative to the axis of the cathode ring 22, is a stud-like structure 46 having a somewhat concave conical surface of revolution 48 symmetrically disposed on the axis of the ring 22. The stud structure 46 will be referred to as a probe electrode in the discussion of the operation of the gun structure below.

An object aperture electrode for selectively masking the electron beam is formed as a circular disk 50 having at its center a cup-like depression 52, the bottom of which is formed by a plate normal to the axis of cathode 22 and has an aperture 54 at the center. A first accelerating electrode 56 is formed as a short cylindrical element fixed by short studs 58 to the glass rods 30. Electrode 56 has an end wall portion 60 with an opening at its center, which is surrounded by a short tubular extension 62 extending outwardly from wall 60 and into the apertured depressed portion 52 of electrode 50.

A second accelerating electrode 64 is coaxially aligned with the axis of the annular cathode 22. Electrode 64 is a tubular member having an enlarged portion 66 at the end farther from the cathode electrode. A conductive wall coating 68 is formed on the inner surface of the tube neck 12 and extends into the bulb portion 10 to a point adjacent to screen 16, as shown in Figure 1.

The cathode electrode 22 is heated by a heater filament 70 consisting of an electrical coil positioned within the channel of electrode 22. The control grid rings 32 and 34 are maintained at a common potential and are biased negatively with respect to the cathode electrode 22. Rings 37 and 39 are accelerating electrodes and are operated at a common positive potential or at different positive potentials as shown in Figure 2. The probe electrode 46 is held at ground potential or a few volts negative to cathode, while the apertured object electrode 50 is operated somewhere within the range of 20 to 200 volts positive relative to ground potential, depending upon the desired operating characteristics of the tube. Accelerating electrode 56 is held within a range of 500 to 4,000 volts positive, while electrode 64 is operated at around 5,000 volts, and the wall coating electrode 68 at 20,000 volts.

During tube operation, the control electrodes 32 and 34, the accelerating electrodes 37 and 39 and the probe electrode 46 produce an electrostatic field which first accelerates the electrons through the annular aperture be-

tween the control grid portions 36 and 38 and directs the accelerated electrons radially inward and then directs the accelerated electrons axially relative to the axis of cathode 22 and focuses or converges the electron flow onto the apertured electrode 50, normal to the axis of cathode 22. The paths of the electrons will terminate at the object electrode 50 or will pass through the central aperture 54 in this electrode. The electrons passing through the aperture 54 are accelerated and focused by the electron lens fields between electrodes 56 and 64 and between electrode portion 66 and coating 68 to cause the electron paths to converge to a small spot on the fluorescent screen 16.

Figure 4 shows characteristic curves derived from one operation of the tube. Variations in the control voltage applied to plates 32 and 34 are plotted against values of the electron current passing through aperture 54 of the gun. The curves are for different voltage conditions applied to accelerating electrodes 37 and 39, as indicated, in which E_{37} is the voltage applied to electrode 37 and E_{39} is the voltage applied to electrode 39. During these several operating conditions, the probe electrode 46 was operated at ground or cathode potential, the apertured electrode 50 at about 50 volts positive relative to ground, and accelerating electrode 56 at around 500 volts positive relative to ground.

Each of the curves of Figure 4 indicates a novel characteristic of the gun under the conditions of operation. The gun has cutoff of beam current at a negative potential greater than the -45 volts shown in Figure 4. The beam current through aperture 54 increases as the control grid (32, 34) becomes less negative and reaches a maximum at a relatively small negative potential relative to cathode potential. Then the current drops off very quickly to a cut-off potential of the control grid which is still negative relative to cathode or zero potential. The slope of this current drop is very steep and the curves (to the right of the peaks) indicate that the tube may be operated with only a few volts drive between maximum current and cut-off potential which, as in the case of curve A, is as low as 5 volts. This small voltage drive is a characteristic of the novel gun structure and has a distinct advantage in that less amplification of the signal voltage is required before it is applied to the control grid electrodes.

The sudden drop in current as shown in Figure 4 from a maximum to a minimum at close to zero potential is due to a type of focus modulation of the electrons between the cathode surface and the aperture 54. When the tube is operated at the peak of the curve, the current passing through aperture 54 is a maximum, since the electron emission from the cathode surface is focused into aperture 54 to provide a high density of electrons within the aperture. However, as the control electrodes 32 and 34 are made more positive, the electron flow becomes defocused and there is a reduction in the electron density at the center of the electron stream which continues to drop until no current passes through aperture 54, and the beam current beyond aperture 54 falls to zero. These results occur since the electrons coming from the cathode surface are focused to form a conical hollow beam in the region adjacent to accelerating electrode portion 52. The conical beam has an apex at the aperture 54 when the beam current is maximum, but as the control grid electrodes 32 and 34 are made more positive, the conical beam, because it becomes defocused, widens and more and more of it strikes the periphery of aperture 54 and the electrode portion surrounding the aperture until a point is reached where the recessed portion 52 surrounding aperture 54 collects all of the beam electrons. Thus, the control grid electrodes 32-34 function to control the current flow from the cathode electrode 22, and also control the focus characteristics of the field formed by the electrodes between the cathode

22 and electrode 50, to provide focus modulation of the electron beam.

The electrons emitted from the surface of cathode 22 first flow inwardly in a radial direction between the electrode portions 36 and 38 and are then deflected up along the axis of the cathode 22. However, those electrons leaving the cathode surface with tangential velocity components other than perpendicular to the gun axis will tend to miss the axis of cathode 22 and spiral around the probe 46 to strike adjacent electrode surfaces. That is, the field configuration between cathode 22 and probe surface 48 provides a velocity selection of those electrons emitted from the cathode surface substantially perpendicular to the gun axis. The finite angular momentum of other electrons emitted from the cathode surfaces prevents them from reaching the gun axis and they do not thus form a part of the beam passing through aperture 54. In this manner, the beam electrons passing through the object aperture 54 are those having substantially the same velocities. This tends to eliminate fringe electrons passing through the focusing fields between electrodes 56 and 64 and between electrode portion 66 and coating 68. Such fringe electrons normally pass through the outer regions of the focusing lenses which regions provide aberration effects with a resulting distortion of the beam spot on the phosphor screen 16. The novel gun structure described thus provides a tube having better spot formation at the screen and thus higher picture resolution.

Since the aperture 54 is imaged at the phosphor screen 16, the size of aperture 54 is made very small, in the order of 7 mils in diameter. This provides a constant beam spot at the screen, which is independent of the beam current passing through aperture 54. Furthermore, since the cathode surface 22 is completely out of alignment with the gun axis passing through aperture 54 any positive ions generated by the beam along its path will pass back through aperture 54 toward the probe 46. These positive ions will not be deflected to strike the surface of cathode 22, but will terminate on adjacent electrode structures. This then prevents deterioration of the cathode emitting surface due to positive ion bombardment.

The voltages given above are typical of those used in a gun structure constructed in the manner described. The following dimensions are given also by way of example only and are those which have been used in a tube of the type described. The spacing between the cathode surface 22 and the overlying electrode portions 36 and 38 is 5 mils. The spacing between the edges of the aligned cylindrical control electrode portions 36 and 38 is 15 mils, while the spacing between control electrode portions 36 and 38 and accelerating electrode portions 40 and 42 respectively is about 20 mils. The annular spacing between the accelerating electrode portions 40 and 42 is 30 mils, while the spacing between the tip of the probe 46 and the aperture 54 is 50 mils. Probe 46 is 80 mils at its base, while the cathode ring 22 has an inner diameter of 200 mils. It was stated that the conical surface 48 of probe 46 is slightly curved or concave. This surface was formed with a radius of 220 mils.

The cylindrical control grid portions 36 and 38 have been described and shown in Figure 2 as portions respectively of different plates 32 and 34. Under some conditions of operation, however, it is possible to form the control grid portions 36 and 38 from a single cylinder in which the center portion overlying the cathode emitting surface is cut out. With this structure, spokes are obviously necessary to keep the end portions of the common cylinder apart. These spokes extending down across the cathode surface, however, will distort the accelerating field between the cathode surface and the conical surface 48 of probe 46. This field distortion will result in more of the electrons emitted from the cathode surface spiralling around the probe and be collected by neighboring electrode structures, rather than passing axially through the grid aperture 54.

The cylindrical accelerating electrode portions 40 and 42 are respectively shown in Figure 2 as being operated at different potentials. This difference of potential bends the accelerating electrostatic field in the region of the cathode so as to refract the electrons emitted from the cathode surface slightly away from surface 48 of the probe and to aid in their alignment with the cathode axis. A similar effect can be produced by changing the symmetry of electrode portions 40 and 42 and operating them at a common potential. In Figure 5, for example, cylindrical electrode portion 40 is substantially that shown in Figure 2. However, electrode 42 of Figure 2 is replaced by a cylindrical electrode portion 42' having a thicker wall than cylindrical portion 40. Thus, the inner surface 15 of cylindrical electrode portion 42' extends farther in toward the axis of probe 46. The spacing, then, between cylindrical portions of 40 and 42' is such as to change the accelerating field in this region as to provide a bending of the electrons flowing radially from the cathode surface 20 and to impart to them an axial component of direction 25 away from the probe surface 48. A similar result can be obtained with the structure of Figure 6 in which the wall thickness of cylindrical electrode portions 40 and 42'' are substantially the same, but the diameter of cylindrical portion 42'' is smaller than that of electrode portion 40. This difference in diameter dimensions is small and is in the order of a few mils.

Since the novel gun described above uses a low voltage drive, tube 10 can be used in a television receiver circuit 30 without the need for signal amplification beyond the video detector stage. However, in such an application video amplification is still needed to provide the necessary sync signal and AGC gain.

The particular gun structure shown in Figures 2 and 3 35 may be operated to provide necessary video amplification for these and other purposes without a video amplifier tube. During the operation of the gun of Figures 2 and 3, current flows to electrode portion 42. If an appropriate load impedance is placed in the voltage supply lead 40 of electrode 42, an amplified video output signal is available at this lead. This is possible since the current flow to electrode 42 is controlled by the video input signal applied to control grid 32-34. A similar effect may be obtained by using apertured electrode 50 as an anode of the amplifying triode.

45 The annular electrode geometry employed in this new gun distinguishes it from other gun designs. It permits the use of a large cathode emitting area. The heater power, however, is the same as that consumed by standard design guns. A gun of this geometry offers very high modulation sensitivity (low drive requirement) high resolution, focus independent of beam current, low cathode loading, and freedom from cathode ion bombardment.

What is claimed is:

1. An electron gun for a cathode ray tube, said gun comprising an annular cathode electrode having an electron emitting inner surface, a reflector electrode having a portion thereof coaxially mounted within said annular cathode, and a plurality of annular electrodes including a control electrode, said electrodes having portions positioned between said reflector electrode and said cathode surface for providing accelerating and focus modulating electrostatic fields between said cathode and said reflector electrodes, said annular electrode portions including a first pair of tubular members having substantially equal diameters mounted coaxially within said annular cathode with adjacent ends spaced from and aligned with each other, and a second pair of tubular electrode members coaxially mounted within said cathode electrode between said first pair of tubular members and said reflector electrode, said second pair of tubular members being spaced along said cathode axis from each other.
2. An electron gun for a cathode ray tube, said gun comprising an annular cathode electrode having an electron emitting inner surface, a reflector electrode having

a portion thereof coaxially mounted within said annular cathode, a plurality of annular electrodes including a control electrode, said electrodes having portions positioned between said reflector electrode and said cathode surface for providing accelerating and focus modulating electrostatic fields between said cathode and said reflector electrodes, and an accelerating electrode spaced from said cathode electrode along the axis thereof, said accelerating electrode having an aperture therethrough and on the axis of said annular cathode.

3. An electron gun for a cathode ray tube, said gun comprising an annular cathode electrode having an electron emitting inner surface, a reflector electrode having a portion thereof coaxially mounted within said annular cathode, and a plurality of annular electrodes including a control electrode, said electrodes having portions positioned between said reflector electrode and said cathode surface for providing accelerating and focus modulating electrostatic fields between said cathode and said reflector electrodes, said annular electrode portions including a first pair of tubular members having substantially equal diameters mounted coaxially within said annular cathode with adjacent ends spaced from and aligned with each other, and a second pair of tubular electrode members coaxially mounted within said cathode electrode between said first pair of tubular members and said reflector electrode, said second pair of tubular members being spaced along said cathode axis, said reflector electrode portion having a conical surface coaxial with said annular cathode, the spacings between said adjacent ends of said first pair of tubular members and between said second pair of spaced tubular electrodes being aligned with said cathode emitting surface and said conical reflector surface, and an accelerating electrode spaced along said cathode axis from said conical reflector surface, said accelerating electrode having a central aperture on said cathode axis.

4. An electron gun for a cathode ray tube, said gun comprising a cathode electrode for providing a source of electrons, electrode means arranged adjacent to said cathode electrode for forming electrons from said cathode electrode into an electron flow, and an apertured electrode offset from said electron flow, said electrode means including structure between said cathode and said apertured electrode for focusing said electron flow onto said apertured electrode, said structure comprising means for

changing the focus of said electron flow on said apertured electrode and for controlling the electron current in said flow of electrons, said electrode means including a probe electrode positioned in the path of said electron flow to deflect said electron flow toward said aperture electrode.

5. An electron gun for a cathode ray tube, said gun comprising a cathode electrode having an arcuate concave electron emitting surface, a reflector electrode having a portion thereof concentrically mounted relative to said arcuate cathode surface, an apertured electrode spaced along the axis of said arcuate cathode surface from said reflector electrode, and a plurality of electrodes including a control electrode, said electrodes having portions positioned between said reflector electrode and said cathode surface for providing an accelerating electrostatic field between said cathode and said reflector electrode and for focusing electrons from said cathode surface onto said apertured electrode.
- 10 6. An electron gun comprising means for initiating an annular electron emission, means for establishing a flow of the electrons of said emission radially inward toward the axis of the annulus of said annular emission, means for deflecting said flow to along said axis, electric field means including means for accelerating said electrons radially inward and for selectively variably focusing said electron flow and electron beam masking means disposed in said axial beam path.
- 15 7. An electron gun comprising means for initiating an annular electron emission, means for establishing a flow of the electrons of said emission radially inward toward the axis of the annulus of said annular emission, means for creating an electric field to deflect said flow to along said axis, means for shaping said electron deflecting field to focus said electron flow along said axis, means for partially masking said electron flow at a point along said axis, and means for modulating the focusing effect of said field to vary the amount of electron flow past said point.
